(57) **CLAIM**

The ornamental design for a medical imaging device as shown and described.

DESCRIPTION

FIG. 1 is a top-front-left perspective view of a medical imaging device according to a first embodiment of the claimed design.

FIG. 2 is a bottom-rear-left perspective view of the medical imaging device of FIG. 1.

FIG. 3 is a bottom-front-right view of the medical imaging device of FIG. 1.

FIG. 4 is a top view of the medical imaging device of FIG. 1.

FIG. 5 is a bottom view of the medical imaging device of FIG. 1.

FIG. 6 is a left side view of the medical imaging device of FIG. 1.

FIG. 7 is a right side view of the medical imaging device of FIG. 1.

FIG. 8 is a rear view of the medical imaging device of FIG. 1.

FIG. 9 is a front view of the medical imaging device of FIG. 1.

FIG. 10 is a top-front-left perspective view of a medical imaging device according to a second embodiment of the claimed design.

FIG. 11 is a bottom-rear-left perspective view of the medical imaging device of FIG. 10.

FIG. 12 is a bottom-front-right view of the medical imaging device of FIG. 10.

FIG. 13 is a top view of the medical imaging device of FIG. 10.

FIG. 14 is a bottom view of the medical imaging device of FIG. 10.

FIG. 15 is a left side view of the medical imaging device of FIG. 10.

FIG. 16 is a right side view of the medical imaging device of FIG. 10.

FIG. 17 is a rear view of the medical imaging device of FIG. 10; and,

(Continued)

FIG. 18 is a front view of the medical imaging device of FIG. 10.

The broken lines in the drawings illustrate portions of the medical imaging device that form no part of the claimed design.

The stipple shading shown in FIGS. 10-18 represents contrast in appearance, although no particular color is claimed.
